METHOD OF MULTICOLOR PRINTING

Franz Weiss, Park Ridge, Ill.

Application November 15, 1939, Serial No. 304,506

5 Claims. (Cl. 101—211)

My invention relates to a method of multicolor printing and to a single plate from which multicolor prints may be obtained.

It has long been true that in known multicolor printing methods that they are limited in that they can only print one color at a time from one plate under normal conditions. They can print tints or shades of varying strength of one color by breaking up the printing-area into dots, called 10 halftone. But several colors of entirely different hue cannot be printed simultaneously except if the respective color areas are far enough apart to allow separate rolling or inking up. But under normal conditions all printing processes apply their colors to the printing plates, from which the inks or colors are transferred to the surface to be printed. They all, for this reason, are limited to one color at a time.

This means that any reproduction of a colored subject or illustration requires at least three colors, mostly four, in lithography up to six or seven colors and in other special printing processes i. e., rubberplate, silkscreen process, woodblock, etc., even more. An increase in the number of colors is especially necessary if these colors are supposed to be solid colors, as for example for decorative purposes in wallpapers, where normally no halftone is used.

Any increase in the number of colors therefore 20 increases the cost of the print and it is evident that very considerable savings could be accomplished if all colors could be printed with one impression.

The solution of the above problem is among 30 the objects of my invention, which permits printing or transferring of any number of colors from the plate to the surface to be printed on, with one impression. I accomplish this only by a radical departure from the present methods 40 where the printing-plate is always a body of metal, rubber, wood, linoleum, silk, etc., to which and from which color is applied for the process of printing.

I make my new plates from the printing-colors 45 themselves, and impressions are taken or lifted off from these mosaic-like plates by moistening of the surface to be printed with the proper solvents.

My method of multicolor printing and my 50 multicolor printing-plate include such other objects, advantages and capabilities as will later more fully appear and which are inherently possessed by my invention.

While I have shown in the accompanying 55 drawings and described in the specification a

preferred method and a preferred embodiment of my article of manufacture, yet I wish it understood that the same are susceptible of modification and change without departing from the spirit of my invention.

Referring more particularly to the drawings, I have illustrated therein the steps of my detailed method, as hereinafter set forth.

Fig. 1 is an elevational view of the tracing of a subject on a sheet of tracing paper; Fig. 2 is a perspective view of the mounting and rolling of the tracing on top of a flat sheet of formable material to form a formsheet; Fig. 3 is a perspective view of the cutting to the formsheet with a stencil knife; Fig. 4 is a perspective view of the cutting of the formsheet with a coping saw into segments; Fig. 5 is a perspective view of the placing of the segments in a lubricant pan; Fig. 6 is a perspective view of the lubricated segments laid on a flat sized support in the same relation 20 to each other that they were in the formsheet; Fig. 7 is a perspective view of the removal of certain segments; Fig. 8 is a detailed view of two of the segments; Fig. 9 is a perspective view showing the pouring of coloring into the spaces formerly occupied by the removed spaces; Fig. 10 is a perspective view after the pouring of the coloring has been completed, with a temporary margin; Fig. 11 is a perspective view showing the 25 pouring of the molten material over the segments; Fig. 12 is a perspective view of a support; Fig. 13 is a perspective view showing the dissolving away of the sizing; Fig. 14 is a perspective view showing the building up of a permanent 30 surrounding edge; Fig. 15 is a cross sectional 35 view of a finished color plate; Fig. 16 is a bracketed view showing detailed views of a block of paper, a sheet therefrom and a can of solvent; Fig. 17 is a perspective view showing the rolling of the sheet of paper over the color plate, and 40 Fig. 18 is an elevational view of the print obtained from the color plate.

My preferred method of multicolor printing comprises tracing or drawing a full sized subject on a sheet of tracing paper, as shown in Fig. 1, 45 and mounting or applying this drawing T, as shown in Fig. 2, on top of a flat sheet of wax, soap, clay compound or any material W that will hold its shape and which can be readily cut into smaller pieces, to form a formsheet F. The 50 tracing paper portion T of the formsheet F is then cut with a stencil knife K or the like, as shown in Fig. 3, into as many parts as there are color areas in the subject. The formsheet F is then cut through along the cut lines in the trac- 55

- ing paper T with a fine wire attached to a coping saw O, as shown in Fig. 4, into as many segments or pieces S as there are color areas. Care must be taken that the cuts are perfectly vertical. A push pin or nail P is stuck into each of the cut mosaic-like pieces S of the formsheet F, and each segment S is placed in a lubricant L which is in a pan, as shown in Fig. 5, and lubricated to prevent sticking and to provide sliding. The lubricated mosaic-like segments S are then laid on a flat sized support Z, as shown in Fig. 6, in the same relation to each other as they were in the formsheet F. When all of the segments S have been assembled, like the parts of a jigsaw puzzle, a certain segment or segments S are removed, as shown in Figs. 7 and 8, and ink or coloring C of a desired color or shade is poured or dropped into the space formerly occupied by said segment or segments, as shown in Fig. 9. The ink or coloring C will rapidly set and harden and will not stick to the lubricated walls of the adjacent segments S. In this way each segment S is replaced by the color it represents by a segment of color C.
- When the pouring of the colors or inks is completed, the edges of the segments C are protected from breaking down by the remaining segments S forming a temporary margin M, as shown in Fig. 10.
- To build the color plate R formed from the segments C up to uniform thickness I build a border B of wood or the like around the color plate and then fill it with molten wax or plaster of Paris A, as shown in Fig. 11. Before this filling is cooled or set I put a support X, as shown in Fig. 12, of board, glass, metal, cardboard or screen down on top of the filling A and let them bind together. When cool I turn it over, remove border B and dissolve away the sizing Z, as shown in Fig. 13, rinse and wipe the color plate R formed from the color segments C, which is now bottom up, very carefully with plenty of water, or a suitable solvent.
- With this procedure, I get a reverse looking plate in order to obtain a right print, and furthermore I thus obtain a perfectly even and smooth printing surface in my color plate R. I then remove the segments S forming the margin M and make a permanent surrounding edge E of plastic material, as shown in Fig. 14. A cross section of the finished color plate R is shown in Fig. 15.
- In order to print I take a sheet of paper, cloth for textile printing, or any suitable material H and moisten it with a solvent V, as shown in Fig. 16, and bring it in contact with the color plate R, apply sufficient pressure with a roller Y, as shown in Fig. 17, lift the paper from the plate to which it sticks and the print is finished, as shown in Fig. 18. Every color of the mosaic-colorplate is given off by the action of the solvent in the paper with one impression. A color print is thus obtained that carries all the colors of the plate.
- The above preferred method is adapted for the reproduction of such large or bold subjects as billboard posters, signs, window displays, wall paper, banners, or the like, wherein there are flat colors and no blendings or washes, and wherein color is predominant.
- In my method I may trace the design or subject directly onto the material base W and thus eliminate the tracing paper T and the applying of the tracing paper T to the material base W.
- The step of my method of cutting the tracing

paper T while on the form sheet F may be omitted, and the material base W may be cut vertically into segments S by following the lines marked thereon.

Instead of the filling in step shown in Fig. 11, I may obtain uniform thickness of the color plate R by shaving down its exposed face with a heated blade, and print from the thus obtained flat, even face of said color plate.

In my method the inks or colors used have the following properties:

1. Extreme firmness or hardness, so that when printing is done from them the plates stand up under the pressure of the roller and hold the exact shape of each individual color area in the printing plate.

2. Extreme concentration of color so that as many impressions as possible can be taken from a plate of a given thickness.

3. Sufficient solubility, so that when a paper is moistened with a proper solvent and pressed against the plate, momentarily enough colored ink from the plate is dissolved and taken up by the paper to give a strong print.

4. Proper chemical formulation with sufficient thermoplastics such as resins and waxes to give all the necessary firmness in the cold, and low enough melting point so that when heated in the water bath the colors or inks soften around 120 to 150 degrees Fahrenheit or melt at about 150 to 180 degrees Fahrenheit. These approximate softening and melting ranges are necessary to facilitate the making of the color plates.

5. The inks must be non-drying and not changing as long as incorporated in the plates, so that plates can be stored away under proper precautions, and reprints be made even after a year or more. The inks must be quick drying when dissolved and transferred in printing onto the paper, which can be accomplished by the use of proper solvents, i. e., low boilers.

6. Absolute uniformity in body and strength of all different colors or inks, so that the same amount of color is lifted off from the color areas during printing.

With inks, incorporating these properties, it is comparatively easy to make a multicolor printing plate for as many colors as wanted, but the plates may be somewhat restricted in the reproduction of detail, which means the finer the detail in the plates the more difficult it becomes to make the plates.

If the colors are not in flat, distinct areas, but blended or washed out, I use the form sheet only as an auxiliary medium to define certain areas in the drawing. Each area might have a number of different colors or tints and shades, and to reproduce these fairly faithfully it is difficult to pour molten inks into such a space because I might have to put a dozen or two different colors or shades into this area and it might be too small to cut out from the form sheet. To do this fairly quickly and dependably I soften the ink to a consistency of artist oil color, and squeeze the colors out through the fine nozzles of the tubes onto the glued support to form fine lines, dots or patterns. Since the inks are rapidly setting, they do not flow out and form raised lines. This layer of various colored fine lines and dots is, of course, by far not so thick as a poured layer of one color which I can pour in one operation in any thickness wanted, but has to be built up to the required thickness by repeating the operations with the tubes with the same colors as previously and as

much as possible following the same drawing or patterns.

This procedure requires of course much more work, but allows reproductions of paintings, water colors, or the like.

Prints of subjects with detail may be reproduced in small runs or quantities of 500 to 750 from one plate so made, since a plate built up from fine lines and dots must necessarily have a limited thickness, while poured plates with larger individual color areas allow much greater thickness, up to one inch or more, which plates give of course correspondingly more prints. My numerous trials with improved inks of good firmness and extreme concentration give me at least 1000 impressions from a one-quarter inch thick color plate. Thinner or thicker plates correspondingly less or more.

It is understood that plates do not have to be made exactly by the foregoing mentioned methods, but that the procedure can be modified as the particular case might warrant, i. e., it may prove more practical to produce lines or shading, or line technique of an art work by pouring first the predominating color and then by lifting out with a graver these lines or small details from the color plate and squeezing different colors into these grooves. This can be facilitated by somewhat warming the color plate from top or bottom to soften the set and hardened colors which can be worked or grooved easily in the softened stage. There are many ways of simplifying or modifying the general procedure by the use of preformed letters, borders, decorative designs and the like, but all these things are merely alternatives of the foregoing description.

The basic principle is forming a plate with the colors themselves and to do this properly the colors have to have the before-mentioned properties. The most important property, which makes this method possible, is their thermoplastic nature. They must be firm when cold and soft and workable when warm or hot. This is accomplished by incorporating thermoplastic materials, like natural resins, synthetic resins and waxes, into the mixture.

I have produced colors or inks of three different basic groups: (a) varnishes or oils—resin mixtures, soluble in hydrocarbons, or solvents of coal tar or similar derivatives; (b) lacquers—resin mixtures, soluble in their thinners; (c) gums—water soluble resin mixtures, soluble in water.

A wide variety of inks can be produced this way and they can be adjusted to print all kinds of colors or dyes, (pigments, toners, lakes and dyes), on all kind of materials. My water soluble thermoplastic water color ink is perfectly suited for multicolor textile printing of any kind of dye on any kind of fabric. The fixing agent for the dye (to bind dye to the fiber), is added to the water with which the fabric is moistened for printing.

The use of a particular ink necessitates of course the choice of the proper material for the form sheets and their lubricants.

For the form sheets, when harder cutting materials like wood, linoleum, rubber or the like are not wanted, I either pour wax into sheets, which wax is first chemically treated and softened so that it cuts cold with a wire but still holds perfectly its shape, or roll special soap into sheets of required thickness, or I use a special very firm clay compound of very little shrinkage.

All cut out pieces of the form sheets have to be lubricated to prevent sticking together and sticking of inks to the side walls. Only a very thin layer is necessary and advisable, since a thicker layer would make it difficult to lift the individual pieces out from the assembled mosaic form sheet.

As a rule it is safe to use a saponified water as a lubricant for the varnish and lacquer inks and a wax solution for the water color or dye inks. Generally speaking, the lubricant should be non drying and not mix with the colors. Proper lubricating prevents bleeding of colors into neighboring areas too.

The inks are in the cold so heavy, contain so little solvents, that they hold their colors perfectly in suspension. They allow and preserve perfect lines between the different color areas and do not mix, run together or blur the lines unless they are heated on the color plate to promote flow, to soften lines and make tints and shades flow together.

It is evident that this method offers tremendous advantages when combined with other printing methods. Any number of colors can be printed by these color plates and detail and copy by any other method, for example for maps, color charts, fashions, interiors, etc., wherever color is important.

Having thus described my invention I claim:

1. The method of multicolor printing comprising applying a tracing sheet to a flat body of cuttable material to make a formsheet, vertically cutting said formsheet into segments, each segment representing an area for a desired color, lubricating said segments, removing the segments one or more at a time and filling each space with a printing material of a desired color to form a color plate, applying a support to the face of the color plate, turning the color plate over, and applying a solvent treated surface to the back of the plate to obtain a multicolor print with one impression.

2. The method of multicolor printing comprising forming a flat cuttable formsheet, cutting the formsheet into segments for color areas, removing the segments one or more at a time and filling each space with printing material of desired color to form a color plate, and applying a surface to the color plate to obtain a multicolor print with one impression.

3. The method of multicolor printing comprising making a tracing of the subject of the print desired on thin tough tracing paper, applying said tracing paper to a flat body of cuttable material to form a formsheet, cutting through the tracing paper on lines defining certain desired color areas, cutting vertically through said form sheet along the cut lines of the tracing paper to create a plurality of segments, removing each of said segments, lubricating the same so that they will slide and will not stick and replacing them in their original relative positions, again removing each of said segments one or more at a time and filling each space with ink of desired color to form a color plate, placing a border of colorless material around said color plate and filling in over the face of said color plate to form a support, turning the color plate over, dissolving off the sizing on the bottom of said color plate, and applying solvent treated surfaces to said exposed color plate to obtain a plurality of multicolor prints, each print being obtained with a single impression.

4. The method of multicolor printing comprising

ing forming a formsheet, cutting the formsheet into segments, removing the segments one or more at a time, pouring in printing material of a desired color in said spaces, adding printing material of other desired colors in desired spots in the spaces to fill the same, and applying a surface to the color plate to obtain a multicolor print with one impression.

5. The method of multicolor printing compris-

ing forming a formsheet, cutting the formsheet into segments, removing the segments one or more at a time, pouring in printing material of a desired color in said spaces, removing some of the printing material in desired spots and placing thereon other printing material of desired color, and applying a surface to the color plate to obtain a multicolor print with one impression.

FRANZ WEISS.
